United States Patent Office.

JAMES H. FERGUSON AND HENRY W. LOVEJOY, OF NEW YORK, N. Y.

Letters Patent No. 63,491, dated April 2, 1867.

IMPROVED MACHINE FOR TRIMMING METALS.

The Schedule referred to in these Letters Patent and making part of the same.

TO ALL WHOM IT MAY CONCERN:

Be it known that we, J. H. FERGUSON and H. W. LOVEJOY, of the city, county, and State of New York, have invented a new and improved Machine for Trimming Metal and other Plates; and we do hereby declare that the following is a full, clear, and exact description thereof, which will enable others skilled in the art to make and use the same, reference being had to the accompanying drawings, forming part of this specification, in which—

Figure 1 represents a longitudinal vertical section of this invention.

Figure 2 is a plan or top view of the same.

Figure 3 is a detached side elevation of the clamp which serves to retain the plates to be edged.

Similar letters of reference indicate like parts.

This invention relates to a machine by which the edges of metallic or other plates can be chamfered off and the roughness removed, leaving the edges round and smooth. This operation is generally performed by the use of a plane worked by hand, the sharp corner of the bevel being removed to prevent injury to the hands of the workmen by a subsequent operation, thus requiring much hand labor and time. In the machine which forms the subject-matter of this invention the plates to be trimmed are secured by suitable clamps on a slide or carriage, which moves in front of a revolving cutter-head, and of a stationary knife, in such a manner that by the cutters in the revolving head one edge after the other of the plate is chamfered off, and the sharp corner removed by the stationary knife, all by one operation.

A represents a circular head, which is mounted on the end of a spindle, B, to which a rapid revolving motion is imparted by a belt, or any other similar means. In the cutter-head are secured two or more cutters, C, in a suitable position to act on the edge of the plate to be trimmed. The spindle B has its bearings in an adjustable head-stock, B'. This plate is secured by screw-clamps, D, or any other suitable means, to a slide or carriage, E, which moves freely in a groove, a, in the table or platform F. This table is supported by set-screws, l, whereby it can be adjusted to any desired bevel, and it is adjustable towards and from the cutter-head. It is also provided with a gauge, I, which is hinged so that it can be readily turned up out of the way, and which may be made adjustable towards and from the carriage E in any suitable manner. By means of this gauge the plate to be trimmed is adjusted in such a position that the cutters in the revolving head will chamfer off the edge to the desired extent, and the sharp corner formed by this operation is removed by a stationary knife, H, which is secured in the table or platform in the proper position. In order to get the plate square or to the desired shape, a straight-edge, G, may be applied to one of the clamps, and this straight-edge may be so arranged that it is adjustable to any desired angle.

The operation is as follows: After the cutters have been properly adjusted the plate to be operated upon is placed on the table and properly gauged, the clamps are tightened, and the plate is passed along on the table past the rapidly-revolving cutter-head and the stationary knife. By these means the edge of the plate is bevelled, and the sharp edge removed at one operation. The clamps secured to the sliding carriage prevent the plate moving out of its position, and said plate can be bevelled off with the greatest ease and facility. In using our machine for stereotype plates we obtain the particular advantage that we can trim the edges close to the body without danger of cutting away the face of the type.

Having thus described our invention, we claim as new, and desire to secure by Letters Patent—

The clamps D and carriage E, in combination with the table F, cutter-head A on the adjustable head-stock B', and stationary knife H, all constructed and operating substantially as and for the purpose described.

JAMES H. FERGUSON,
HENRY W. LOVEJOY.
